PERSONALIZING CALENDARS BY PRINTING PRESS

Edward W. Peterson, St. Paul, Minn., assignor to Brown & Bigelow, St. Paul, Minn., a corporation of Minnesota

Application November 7, 1955, Serial No. 545,250

3 Claims. (Cl. 101—55)

My invention relates to an automatic type changer in combination with a printing press.

I provide apparatus associated with a printing press whereby the printing of an individual line or name on successive sheets in the press is possible and a predetermined number of impressions of the same individual line or name is automatically printed on such sheets. By means of said apparatus a different individual line of type is brought into position in the printing press to repeat the process using other type slugs for the individual impressions upon the successive sheets being printed.

It is a feature to provide apparatus associated with a printing press wherein a plurality of type-slugs are provided and held in readiness for use. The mechanism operates automatically to select the first type slug and move it into printing position. The apparatus is designed primarily for printing an individual's name on a calendar one, four, six or twelve times, depending on the number of sheets which comprise the calendar. The apparatus can be used in combination with a printing press for any form of printing which requires an individual line of type or a limited number of lines of type to be printed on a predetermined number of sheets before a change of type is made.

It is a further feature to provide apparatus cooperating with a printing press which automatically prints a designated type-slug a predetermined number of times, then automatically ejects said type-slug and coincidentally inserts a second type-slug for printing a designated number of sheets; such operation being repeated without interruption to the printing process until all type-slugs contained in the type chase have been used.

It is a further feature to provide apparatus in combination with the printing press which may be set by the operator of the press to print the desired indicia a predetermined number of times. The operation of the apparatus in combination with the printing press is automatic in printing the desired number of impressions of the same indicia and in changing the indicia so that a different printing may be impressed on subsequent sheets in the printing press. The apparatus also automatically engages the type-slugs to bring the same into printing position and then automatically discards the type-slugs from the printing press.

A further object resides in providing a type holding chase which is removably supported in the printing press and which is adapted to hold the respective type-slugs so that they may be selected and moved into printing position in the chase and may be removed after a particular type-slug has served its purpose of printing and a new type-slug is brought into printing position.

An object of the invention resides in providing means whereby the pressman for the press may set a selector switch to cause the printing press to operate to print a predetermined number of impressions before the printing slug is discarded. The apparatus includes timer and selector means which control the printing operation of each slug brought into printing position. The selector

2

means also causes the apparatus to operate pawl means which acts as the ejector means, controlled by a solenoid to eject a type-slug from the printing press after it has served its purpose. Suitable micro switch means prevents the ejector solenoid from operating until the timer cams have advanced to their proper position. This micro switch means is set to close the circuit when the solenoid coil is energized and the plunger is at the end of its stroke. The cam means on the impression cylinder shaft has a long enough dwell to hold the circuit closed until the ejector mechanism operates.

The means by which the foregoing and other objects of this invention are accomplished and the manner of their accomplishment will be readily understood from the following specification and reference to the accompanying drawings which form a part of this specification.

Figure 1 is an end elevation of the printing press and automatic type changer.

Figure 2 is a perspective view of the printing press and type changer, looking at the bed end of the press from the left side, with the press bed in a retracted position.

Figure 3 is a perspective view looking at the bed end of the press from the right side.

Figure 4 shows a circuit diagram for this equipment.

Figure 5 is a perspective view of the control box showing a switch, reset button, selector switch, and pilot light.

Figure 6 is a perspective view of the cam and cam switch which is located on the impression cylinder.

Figure 7 is an enlarged perspective view of a part of the ejector mechanism shown in Figure 8.

Figure 8 is a perspective view showing a portion of the ejector mechanism.

Figure 9 is a perspective view of the ejector slide and frame showing the manner in which the retaining springs are mounted.

Figure 10 shows a perspective view of the rod latch which is located on the ejector slide.

Figure 11 shows an enlarged view of the pawl end of the ejector slide.

Figure 12 is a fragmentary top plan view of the chase, partially broken away and partially in phantom;

Figure 13 is a bottom plan view of the ejector slide and frame of Figure 9, partially broken away, showing the spring, chain, and sprocket means for holding the ejector slide under tension.

Referring now to Figure 1 the frame or chase A is shaped similar to a figure 6 having an end wall 1 and a parallel extended end wall 2 which are connected by the perpendicularly disposed bottom wall 3 and intermediate wall 4 and having the top wall 5 extending perpendicular to the extending end wall 2. This frame is removably attached to the press bed C through bolt means 6. The tension ratchet 7 is attached to the bottom wall 3, by means of the studs 8. Tangentially engageable with the tension ratchet 7 is the actuator pawl 9 and the brake pawl 10, both resistently biased into operative position by springs 9a and 10a respectively as shown in Figure 12. Wound partially upon tension ratchet 7 is the cable means 11; said cable means comprising two cables, one of which is connected by pulleys 11a and 11b through raceways 4a and 4b, in the intermediate wall 4, to one end 12a of type pusher 12. The other cable is connected by pulleys 11c and 11d through raceways 5a and 5b, in the top wall 5, to the other end 12b of the type pusher 12 which is slidably contained between the intermediate wall 4 and the top wall 5. The type chase 13 between the intermediate wall 4 and the top wall 5 contains the type bars 14 when the press is in operation. Mounted in the outer edge of the end wall 1 are the type stops 15 which cooperate with rod latches 19 in guide bar B to position a selected type bar 14a for the printing sequence.

The guide bar B is removably attached to the press bed.

C, by the bolt means 16, distant about the width of one type bar from the outer edge of the end wall 1. Slidably contained in the guide bar B by grooves in the edge of the guide bar facing the end wall, is an ejector slide 17. Figures 9, 10, and 11 which show structural features of guide bar B, are drawn so as to reveal more clearly the manner in which the ejector slide 17 is held in place. For purposes of illustration these figures have been somewhat distorted, their true size and shape relationships being disclosed more accurately in Figures 1-3. As shown in Figure 12, the ejector slide 17 is slidable within guide bar B; the grooves 17a of the ejector side 17 cooperating with the inwardly extending tongue or flange 17b of guide bar B. The ejector slide 17 is held in said guide bar under tension by spring 18, chain 18a and sprockets 18b as shown in Figure 13. When the ejector pawl 31 releases the ejector slide 17, the spring 18, by means of the chain 18a and sprockets 18b pulls the ejector slide 17 back within guide bar B to the position shown in Figures 9 and 13 so that the ejector slide may reciprocate with the press bed C until succeeding type bars are to be received into printing position. The ejector slide 17 contains the rod latches 19 on the outer edge facing the end wall 1 and said rod latches 19 engage the type bars to position said type bars for printing or to eject the type bars when the printing operation has been completed.

The tension ratchet 7 is rotated by the actuator pawl 9 by means of the tension plunger 20. The tension plunger 20 is slidably contained in hole 3a in the bottom wall 3. Contained about the tension plunger 20 is the helical spring 20A. The helical spring 20A is of greater diameter than hole 3a in the bottom wall 3 and is contained between the bottom wall 3 and the end of the tension plunger 20 by suitable retarding means 20B. The tension plunger 20 is actuated by the forwardmost portion of the plunger bracket 21 as hereinafter set forth. The end of the plunger bracket 21 nearest the press bed C is formed with a barrel-like housing 21A through which is fitted the actuating rod 21B. Attached to the end of the actuating rod 21B which extends through the barrel-like housing 21A away from the press bed are the suitable stop means 21C. These stop means prevent the actuating rod from advancing toward the press bed more than a predetermined distance through the barrel-like housing 21A. Encircling the actuator rod 21B is the helical spring 21D between the end of the barrel housing nearest the press bed and the washer and nut means 21E at the end of the actuating rod 21B.

Having thus far described in detail the structural features of the present invention the manner in which it operates will now be pointed out. As shown in Figures 1-3 of the drawings the invention comprehends apparatus for use with a printing press having a reciprocating bed. The press itself forms no part of the invention. In Figure 1, bed C of the printing press is reciprocated back and forth underneath the impression cylinder D as shown by arrow E. The stock to be printed is carried on impression cylinder D throughout a printing cycle. During such a printing cycle the type bar selected for the particular sequence, designated by reference character 14a and positioned between stops 15 and 19, moves with the sliding press bed C under the impression cylinder which rolls the stock in contact therewith. Roller means located behind impression cylinder D provide ink for type bar 14a. Each sheet is discharged from the cylinder after being printed by means not germane to the present invention. After a predetermined number of sheets have been printed with a particular type bar the type bar is ejected in the manner set forth hereinbelow.

In the operation of the press when the press bed reciprocates in a forwardly and backwardly direction, the tension plunger 20 and the plunger bracket 21 are so aligned as to coat axially. When the type-bars 14 in the type chase 13 are advanced so that the leading type-bar is ad-

vanced, the backward tension on the cable means 11 will prevent the tension ratchet 7 from rotating when engaged by the actuator pawl 9. Under these conditions the resistance created by the tension in the cable means 11 and the pressure from the helical spring 20A prevent the tension plunger 20 from sliding inwardly through hole 3a in the base 3 of the chase A. After the ejector mechanism operates, the first type slug will be moved into printing position thereby leaving a blank space between the second type slug and the guide bar B in the type chase 13. Under this condition the backward tension on the cable means 11 is relaxed, and therefore the only resistance to the inward movement of the tension plunger 20 is that provided by the helical spring 20A. Therefore, when the actuator rod 21B coats axially with the tension plunger 20 the spring pressure of the helical spring 21C overcomes the resistance offered by the helical spring 20A and the tension plunger 20 is forced inwardly through the hole in the bottom wall 3. The actuator pawl 9 is thereby engaged against the tension ratchet 7 and rotates it in a counterclockwise direction. The brake pawl 10 prevents the clockwise rotation of the tension ratchet 7. This places the cable means 11 under tension and said cable means being connected by pulleys 11a and 11b to the type pusher 12 causes the type pusher 12 to move toward the guide bar B. This forces all of the type slugs 14, ahead of the type pusher 12, toward the open end of the type chase 13 until the leading type slug comes into contact with the guide bar B. After the type slug is firmly adjacent the guide bar B the tension on the cable means 11 again couples with the action of the spring 20A to provide greater resistance to the inward movement of the tension plunger 20. In such condition the resistance is greater than the resistance of the helical spring 21C, and the actuator rod 21B is again caused to yield rearwardly until another type slug is inserted into printing position.

The plunger bracket 21 is attached to the guard 23, to the left thereof, by means of the tongued plate 23A. The tongued plate 23A is slideably attached to the press by inserting said tongued plate 23A into the groove of the grooved assembly bracket 22. Suitable set-screw means, not shown in the drawings, are utilized to prevent the lateral movement of the plunger bracket 21, the ejector guard 23 and the tongued plate 23A when the press is in operation. The tongued plate 23A is secured to the assembly bracket 22 in such a manner that the actuator rod 21B is in direct alignment with the tension plunger 20.

As shown in Figure 3 attached to the opposite side of the ejector mechanism guard is the ejector solenoid 25 and portions of the ejector mechanism. The ejector mechanism consists of a solenoid 25 which is mechanically connected to the linkages 26, 27 and 28, normally held in a non-operating position by a spring 29 and connected by means of a pin 30 to the actuator pawl 31 contained within the guard 23. The operation of the ejector mechanism is clearly shown in Figures 7 and 8. When the ejector solenoid 25 is energized the ejector pawl 31 engages with the ejector slide 17 of the guide bar B while the press bed retracts to its printing position. When the ejection function is performed, the type bar 14a, which has printed the desired number of impressions, is ejected from between the chase A and the guide bar B and drops into the chute 32 which conducts the type bar to the receptacle 33. While this operation is being performed, the rod latch 19 at the extreme inner end of the ejector slide engages the next type bar and positions it for the next printing. The ejection of type bar 14a from its position intermediate the length of guide bar B to the chute 32, and the simultaneous insertion of a new type bar from the type chase 13 is caused by the relative movement of the press bed C and chase A with respect to guide bar B and the spaced rod latches 19. Latches 19 engage and hold both the type bar 14a to be ejected and the new type bar to be inserted while press bed C is moved rearwardly towards impression cylinder D.

Reference to Figure 4, showing the circuit diagram will reveal the manner by which the ejector mechanism is actuated. The cam switch 34 is located on the press adjacent the impression cylinder. Attached to and turning with the shaft 35 of the impression cylinder is the cam wheel 35A which actuates the cam switch 34 when the cammed surface 35B passes over and depresses the switch arm 34A. This closes a circuit which energizes the solenoid 44. When the solenoid 44 is energized a magnetic field is established which draws the solenoid rod 46 in a downward direction thereby causing the ratchet arm 47 to rotate in a counterclockwise direction. As the ratchet arm 47 rotates the pawl 48 engages one of the teeth on the twelve-toothed gear 36 and advances the toothed gear the distance of one tooth. The restraining leaf spring 49 prevents the toothed gear from rotating in a clockwise direction. On the same shaft with the twelve-toothed gear 36, and turning with it, are three notched cams 37, 38, 39 which operate three micro switches 40, 41 and 42 by means of the pivoted contact arms 50, 51 and 52. The micro switches 40, 41 and 42 are connected to the selector switch 43 which can be set for 1, 4, 6 or 12 impressions. With the press in operation the selected number of impressions are made, and the ejector mechanism operates to eject the used type slug and to automatically insert a new type slug between the frame and the guide bar. The ejector mechanism is actuated when the contact arm actuates the micro switch to close a circuit and energize the ejector solenoid 25. When the ejector solenoid is energized a magnetic field is created and the linkages 26, 27 and 28 are actuated in such a manner as to depress the pin 30, which in turn raises the actuator pawl 31 and causes it to engage the notched end of the ejector slide 17. As the press bed retracts the ejector slide 17 remains in engagement with the actuator pawl 31 thereby ejecting the used type slug and inserting a second type slug into printing position. When this operation is completed the toothed gear will have advanced one tooth, turning with it the notched cams and thereby de-energizing the circuit to the ejector solenoid.

To more clearly explain the operation of the ejector slide, assume that the selector switch has been set for four impressions. Each time the impression cylinder rotates, it will operate the cam switch 34 which in turn will energize the solenoid 44 to advance the twelve-toothed gear 36 one tooth. On the notched cam 37 for four impressions, there are three notches; thus, the micro switch 40 will be actuated three times during a full revolution of the twelve toothed gear 36. It is readily apparent that the impression cylinder 35 will make four impressions between each of the actuations of the micro switch 40. On operation of the micro switch the circuit to the ejector solenoid 25 is closed and said ejector solenoid operates to actuate the ejector mechanism. To prevent faulty operation of the ejector solenoid, a micro switch 45 located in the circuit for said ejector solenoid closes when the solenoid 44 is energized and the plunger is at the end of its stroke. The cam switch 34 on the impression cylinder carries a sufficiently long dwell, or is maintained in a closed position for a sufficient length of time to permit the complete ejection operation before the cam switch is released to its off position.

A number of type slugs, the exact quantity depending upon the size of the type chase and the press bed, are manually inserted into the type chase and are forced by the type pusher until the type slug first in line comes into contact with the frame guide bar. The pressman tending the press sets the switch 53 to the "off" position and then sets the selector switch for the number of impressions desired. The momentary contact reset button 56 is then pushed until the pilot light 54 goes out. The switch 53 is then set in the "on" position and the press is started. The first slug is automatically positioned to print the first number of impressions, the type plunger

actuates the pawl to increase the tension on the ratchet which in turn forces the type pusher against the remaining type slugs in the type chase and thereby positions the second type slug for immediate use. When the desired number of impressions have been made the ejector solenoid is energized and the ejector pawl then engages the ejector slide thereby forcing the used type slug into the chute 32 and simultaneously pulling the second type slug into position for the next series of impressions. This procedure is repeated until all type slugs contained in the type chase have been used for the desired number of times. The printing of the recipient's name upon a calendar adds a personal touch to advertising media, but heretofore has been a costly operation because it was necessary to stop the press and manually insert each succeeding type slug rather than having a continuous automatic operation as provided by my invention.

Heretofore it was impossible to utilize a loose or slideable type slug in a continuous automatic printing operation and as a result personalizing of printed matter was time-consuming and costly.

Except for the insertion of the type slugs at the beginning of each printing operation the printing operation is completely automatic. The calendars or other media upon which printing is desired are automatically fed to the impression cylinder as it is used in the flat bed press.

While only one embodiment has been shown and described, it will be apparent to those skilled in the art that other changes and modifications may be made without departure from the invention. It is therefore, to be understood that it is not intended to limit the invention to the embodiment shown but only by the scope of the claims which follow.

35 I claim:

1. In a printing press having a rotatable impression member and a bed positioned for linear reciprocation below said member, an automatic type changer comprising a chase positioned on the top surface of the press bed, tension and cable means in said chase responsive to the reciprocatory movement of the bed for moving a plurality of type slugs transversely along the forward portion of said chase to an exit at one side thereof, a guide bar positioned on the bed surface in spaced relation along one side of said chase forming a channel therebetween, the forward portion of said channel being adjacent said exit, an ejector bar positioned for slidable engagement into and substantially out of said guide bar, one end of said ejector bar biased to retracted position within said guide bar by spring tension means, the opposite end of said ejector bar extending out from the rearward end of said guide bar, an operating member affixed to the press in stationary position including an ejector pawl having a plurality of actuating linkages, said ejector pawl cooperating with the extending end of said ejector bar for holding it in stationary position in relation to the reciprocatory movement of the bed thereby drawing said ejector partially out of said guide bar and moving one of said slugs along said channel from said exit to printing position and ejecting another slug from printing position from said press, and electro-mechanical means for actuating said linkages responsive to a predetermined number of rotations of the impression member of the press.

2. In a printing press having a rotatable impression member and a planar bed positioned for linear reciprocation below said member, an automatic type changer comprising a chase positioned on the top surface of the press bed, said chase having means responsive to the reciprocal movement of the bed for moving a plurality of type slugs transversely along the forward portion of said chase to a guide bar at one side thereof, a guide bar positioned on said bed in spaced relation along one side of said chase forming a channel therebetween, the forward portion of said channel being adjacent said guide bar, an ejector bar positioned for slidable engagement

into and substantially out of said guide bar and having lug means for moving the type slugs along said guide bar through said channel, electro-mechanical means for actuating said ejector bar comprising in sub-combination, an electric circuit having a first solenoid responsive to the rotation of said impression member for actuating a rotatable ratchet, said ratchet being rotatable on a shaft with a plurality of notched cams, a plurality of micro switches each contiguous with one of said cams and having pivotal contact means actuated by the notches of said cams for momentarily closing the switch, a selective switch adapted to shunt current to said micro switches, one at a time, for energizing a second solenoid when said micro switch is momentarily closed by rotation of the notched cam, and an operating member affixed to said press in stationary position in axial alignment with said ejector bar having an ejector pawl actuated by said second solenoid for cooperating with the free end of said ejector bar to draw it substantially out of said guide bar and simultaneously move said type slugs singly along said guide bar through said channel to printing position and to eject the used type slug from said press.

3. An automatic type-changer for use on a printing press having a rotatable impression cylinder with a planar bed reciprocable thereunder, comprising a first operating member having a chase positioned on the surface of the press bed, cable and spring tensioned ratchet means on said chase responsive to the reciprocation of the bed for moving a plurality of type slugs transversely across the forward portion of said chase to an exit at one side thereof, guiding means positioned on said bed along one side of said chase in spaced relation thereto forming a channel therebetween, the forward portion of said channel being adjacent said exit for receiving the type slugs

therefrom and an elongated ejecting member slidably engaged within said guiding means for reciprocation therein, said ejecting member having means to move said type slugs in one direction along said channel, a second operating member affixed to said press in stationary position for cooperation with said first operating member and having a pawl for contacting said ejecting member and holding it in stationary position against the reciprocatory motion of the press bed whereby said ejecting member slidably engages said guiding means for simultaneously moving said type slugs singly along said channel to printing position and for ejection from said press, and electro-mechanical timing means responsive to the number of rotations of the impression cylinder for moving said pawl into contact with said ejector.
